UNITED STATES PATENT OFFICE.

WILLIAM ARMSTRONG AND WILLIAM ROBERT OWEN CHAMBERS, OF GATESHEAD, ENGLAND.

COMBINED PHOTOPRINTING AND VIGNETTING FRAME.

SPECIFICATION forming part of Letters Patent No. 699,739, dated May 13, 1902.

Application filed July 15, 1901. Serial No. 68,435. (No model.)

To all whom it may concern:

Be it known that we, WILLIAM ARMSTRONG, hair-dresser, residing at 157 Askew road, and WILLIAM ROBERT OWEN CHAMBERS, joiner, residing at 13 Alfred street, Gateshead, in the county of Durham, England, subjects of the King of Great Britain and Ireland, have invented certain new and useful Improvements in Combined Photoprinting and Vignetting 10 Frames, of which the following is a specification.

The invention relates to photoprinting and vignetting frames; and it consists principally in means for connecting the same together and detaching them from each other. The said means consists in providing the vignetting-frame with a metal lug or plate fixed to each side of the same at right angles to its face and clamping the said frame to the printing-frame by means of a thumb-screw passing through a slot in each lug and engaging with a screw-threaded hole on the side of the printing-frame. Spring-clips are also provided for fixing the light-diffuser in position, and a small pin or stop is fixed in each half portion of the back of the printing-frame in such position that the lower edge of each of the spring fastening-arms bears against the same in their locked position and prevents any movement of the back or displacement of the printing-paper.

In order to fully describe the said invention, reference is made to the accompanying drawings, in which—

Figure 1 is a front face view of the vignetting-frame. Fig. 2 is a back view of the printing-frame fixed to the vignetting-frame, and Fig. 3 is a side view of the same.

a is the vignetting-frame, and *b* the printing-frame.

c represents the lugs or plates fixed to the sides of the frame *a*, and *d* represents the slots formed therein, through which pass the thumb-screws *e* for fixing the two frames together.

The frame *a* is of larger size than the frame *b* to admit of angular and lateral adjustment of the vignetting-card. When the two frames are supplied or sold separately, the printing-

frames are provided with two wooden strips 50 *f*, fixed one to each side of the same, to make up any difference in width that may occur between the said frames, the thumb-screws engaging with screwed holes in the plates *g*, fixed to the strips. 55

The light-diffuser *h* is held in position by placing one end under two fixed clips or springs *i* and fixed by turning a single clip or spring *j* (pivoted in a recess *k* at the top of the frame *a*) over the face of the same, the 60 said clips or springs being so formed as to admit and hold securely varying thicknesses of material that the diffusers may be made of. By this means a great saving in time results in fixing and detaching the light-diffuser. 65

The vignetting-frame may be made of either wood or of thin metal plate formed with beaded or thickened edges, the lugs being formed by turning over a strip formed on each side, or they may be separately soldered or riveted 70 thereto. The back *l* of the printing-plate is secured in the ordinary manner by the pivoted springs or arms *m*; but in order to obviate displacement of the printing-paper in the frame each half of the back is provided with 75 the pin or stop *n*, against which the lower edges of the arms *m* bear when they are in their locked position. To facilitate fixing the back in position, one-half of it is marked, as at *o*, and this end is pressed firmly against a 80 similarly-marked end of the frame *b*. The springs or arms *m* are then turned and fastened down over the back *l* by the pivoted plates *p*, their lower edges bearing closely against the pins or stops *n*, so that no movement, however slight, can take place when the paper is 85 being inspected during the course of printing.

The slots *d* in the lugs *c* permit of the adjustment of the frames for varying thicknesses of vignetting-cards and for the insertion of the fingers for manipulating the same. 90

Having now fully described the nature of our said invention, what we claim, and desire to secure by Letters Patent, is—

The improved vignetting attachment for 95 photographic-printing frames comprising a frame *a* fitted with lugs *c* formed with slots *d*, thumb-screws *e* engaging with said slots

for fixing the frame *a* to the printing-frame, and the light-diffuser *h* held in position by clips *i*, *j* in combination with the printing-frame *b* provided with strips *f* and plates *g* formed with screw-holes, the back *l*, stop *n*, marks *o*, and pivoted plates *p*, substantially as described.

In witness whereof we have hereunto set our hands in the presence of two witnesses.

WILLIAM ARMSTRONG.

WILLIAM ROBERT OWEN CHAMBERS.
